LAMP CONTROL MEANS

Graham Trippe, Chicago, Ill.

Application November 15, 1937, Serial No. 174,571

2 Claims. (Cl. 240—61.13)

My invention relates to control means for lamps, usable on boats, trucks or other places and having a construction attached to and passing through a floor, roof or deck and operable 5 at a point remote from the lamp.

Among the objects of my invention is to throw a beam of light from an outside lamp in a desired direction by means of an inside control; to move a lamp in either or both vertical and 10 horizontal planes by remote control; to create a construction having perfect equilibrium and complete balance at all positions of the arc through which the lamp is moved; to provide a construction in which flat metallic tension members 15 will replace the jerkiness caused by stiff linkage with an easy and constant movement in adjustment; to supply a construction that will have no dead center and one that will not cause the lamp to move to extreme positions; to create a construction that will be easier to manipulate, more accurate to position and sure in the 20 retention of a desired position, and such other objects, advantages and capabilities as will later more fully appear and which are inherently possessed by my invention.

While I have shown in the accompanying drawing a preferred embodiment of my invention, yet I wish it understood that the same is susceptible of modification and change without departing from the spirit of my invention.

Referring to the drawing, Fig. 1 is a sectional view of a preferred form of my construction. Fig. 2 is a front view and Fig. 3 is a detailed sectional view thereof.

Referring to the embodiment selected to illustrate my invention, it comprises a lamp 10 having a housing 40, a lens 41, an electric light bulb 42 connected to an electrical source of supply and a reflector 43.

A bracket 11 is attached to the lower portion 40 of the housing 40 by suitable means such as rivets. The bracket 11 has a saddle 12 adapted to receive the upper end of a square terminal member 13 which is attached to the upper end 45 of the tube 14. The terminal member 13 is pivotally attached to the saddle 12.

The tube 14 continues downwardly through a standard 15 to a lower terminal member 16 which is seated in a recess 17 of a rocker arm 18. The lamp 10 is preferably located out doors 50 or in a room or deck higher than the location of the rocker arm. The standard 15 has a base 19 adapted to be attached to the deck, floor or roof 20, by suitable means such as bolts, screws 55 or nails.

A bushing 21 is suitably attached by screw threads to the upper portion or flange 50 of the standard 15, and in a recess 22 of the standard 15 is positioned a packing 23 held in compression against bushing 21, by springs 24. The 5 springs are held by an inward flange 44 of standard 15.

Standard 15 has a downwardly extending flange 25 which extends below floor, deck or roof 20 and is threaded at its lower end to receive a 10 bushing 32.

A handle for the rock arm 18 is preferably provided in the shape of a ball 27 attached thereto by suitable means.

Pivottally attached to the corner 28 of bracket 15 11 is the upper end of flat spring 29. The lower end of flat spring 29 is attached to the outer side of nut 30 by suitable means such as screws. Nut 30 surrounds flange 50 and is rotatable. Nut 30 is prevented by bushing 21 from accidental 20 disengagement.

Pivottally attached to the rocker 18 at its lower end is a flat spring 31 which extends upwardly to nut 26 and is suitably attached to the outer side of said nut 26. The nut 26 surrounds flange 25 25 and is rotatable. Nut 26 is prevented by bushing 32 from accidental disengagement.

When it is desired to tilt the lamp 10 upwardly the user moves the ball 27 in a right downwardly direction. This pushes the tube upwardly so as 30 to move the lamp upwardly on pivot 33 against the resistance exerted by flat spring 29 and on pivot 34 plus the force exerted by flat spring 31. When the user desires to tilt the lamp downwardly he moves the ball 27 in a left upwardly 35 direction. This pushes the tube downwardly so as to move the lamp downward by the force exerted on pivot 33 by flat spring 29 and against the resistance exerted by the flat spring 31 on pivot 34.

A switch 25 is provided on horizontal arm 18 convenient to the reach of the fore finger when the user's hand is on the handle.

Having thus described my invention, I claim: 45

1. A device of the class described comprising a support adapted to be attached to a desired surface, a tube slidably and rotatably extending through said support, a lamp pivotally attached to the upper end of said tube, a remote control handle pivotally attached to the lower end of said tube, an upper flat spring pivotally attached on its upper end to the lamp and on its lower end to the upper portion of the support, a 50 55 60 65 70 75 80 85 90 95 98

- lower flat spring pivotally attached on its lower end to the handle and on its upper end to the lower end of the support, so that upon movement of the handle the tube and the flat springs will move the lamp to a desired position, the tension of one flat spring counteracting the tension of the other flat spring to provide smooth movement of the lamp and to maintain equilibrium of the lamp in all positions.
- 10 2. A device of the class described comprising a support adapted to be attached to a desired surface, a connecting member slidably and rotatably extending through said support, a lamp pivotally attached to one end of said connecting member, a remote control handle pivotally at-

tached to the other end of said connecting member, a flat metallic tension member pivotally attached adjacent one end to the lamp and adjacent its other end to the support and another tension member pivotally attached adjacent one end to the handle and adjacent on its other end to the support so that upon movement of the handle the connecting member and the tension members will move the lamp to a desired position, the tension of one tension member counteracting the tension of the other tension member to provide smooth movement of the lamp and to maintain equilibrium of the lamp in all positions.

GRAHAM TRIPPE. 15
